REFRIGERATION

Andrew A. Kucher, Dayton, Ohio, assignor, by
mesne assignments, to General Motors Corpora-
tion, a corporation of Delaware

Application December 23, 1932, Serial No. 648,694

4 Claims. (Cl. 62—141)

This invention relates to refrigeration.

It is among the objects of this invention to provide a refrigerating apparatus and method which are capable of providing a relatively large amount of cooled drinking water with the aid of a mechanical refrigerating system of relatively small capacity.

It is also among the objects of this invention to provide a refrigerating apparatus and method in which the compressor may operate either continuously or intermittently and in which the power consumption of the refrigerating system is materially reduced automatically while the system continues to operate notwithstanding that the refrigerating capacity of the system exceeds the refrigeration demands placed upon it.

Further objects and advantages of the present invention will be apparent from the following description, reference being had to the accompanying drawing, wherein a preferred form of the present invention is clearly shown.

In the drawing:

The figure shows a vertical cross sectional view of an apparatus embodying features of this invention.

A refrigerating apparatus embodying features of this invention and operating in accordance with my new method of refrigeration includes, in general, an object to be cooled, which in this particular embodiment is a vertically disposed cylindrical water storage tank 10 having an uncooled water inlet 11 and a cooled water outlet 12. This outlet 12 leads to a combined valve and pressure reducer 13 which in turn discharges into a bubbler 14 placed in a basin 15 at the top of the apparatus. The basin 15 is provided with a drain 16 leading to the waste lines of the building. The tank 10 is insulated as shown at 17, and this insulation is covered by a metallic casing 18. Preferably the tank 10, insulation 17 and casing 18 are cylindrical and can be assembled much like the water heaters now in common operation.

A refrigerating system is placed in thermal exchange with the object or water tank in such a manner that a very efficient operation is obtained. To this end, a refrigerant translating device or motor-compressor unit 20, preferably of the type in which the motor and compressor are sealed within a hermetic casing, delivers compressed refrigerant through the pipe 21 to the top of a sheet metal condenser 22. Preferably this sheet metal condenser 22 is made of two sheets of sheet steel or the like which are welded along their edges and at spaced intervals

within the body of the condenser in such a manner that the two sheets are slightly separated but are prevented from spreading away from each other under pressure by the spot-welds along the body thereof. Preferably the condenser 22 is semi-circular or semi-elliptical in shape and is attached to the casing 18 in any suitable manner so that it is spaced a sufficient distance therefrom to permit an induced upward flow of air between the casing 18 and the condenser 22 through the flue-like space 23. The refrigerant is condensed in the condenser and is gathered in a small header 24 and discharges through the pipe 25 to an automatic expansion valve 26. The valve 26 discharges through the pipe 27 to the lower part of a vertically disposed evaporator or evaporating zone in thermal exchange relation with the object to be cooled or liquid in the tank 10. In this particular embodiment, the evaporator is in the form of a sinuously arranged pipe forming evaporating coils 28, 29 and 30 in the tank 10. These coils are preferably separated by panels 31 and 32 to prevent the water entering at 11 from intermixing with the colder water in the lower portion of the tank 10. The evaporated refrigerant discharges through the pipe 33 to a return heat interchanger 34 comprising a sinuous pipe in thermal exchange with the upper part or condensing area or zone of the condenser 22. Thereafter the evaporated refrigerant passes through the atmospheric pre-cooler 35 and returns through the pipe 36 to the motor-compressor unit 20.

The automatic expansion valve 26 is of the type which is responsive to refrigerant pressure in the evaporator, automatically maintains a minimum back pressure in the evaporator. Thus the valve 26 may be so calibrated, that the refrigerant pressure in the coils 28, 29 and 30 cannot drop below the pressure corresponding to the vapor pressure temperature of the refrigerant which would yield a refrigerant temperature of approximately 40° F. more or less, and if the compressor 20 should attempt to reduce the pressure below this point the valve 26 automatically opens to admit more refrigerant and thus prevent the pressure from dropping below the predetermined minimum value. In view of this characteristic of the valve 26, refrigerant will be fed to the lower portion of the evaporator and will first cool the water in the compartment 40. If water is not withdrawn through the bubbler 14 in large quantities, the water in the compartment 40 becomes cooled to the proper temperature and then evaporation in the coil 28 practically ceases, and when more

refrigerant is admitted by the valve 26 in response to the continued operation of the motor compressor unit 20, the liquid refrigerant then rises into the coil 29 where evaporation of the liquid refrigerant cools the water in the space 41. Here again, if no large quantity of water is withdrawn through the bubbler 14, the evaporation of the liquid refrigerant in the coil 29 chills the water in the space 41 until the proper temperature is reached, and thereafter very little evaporation takes place in the coil 29. The liquid refrigerant then rises to the coil 30. In a like manner, evaporation in the coil 30 chills the water in the space 42 and reduces its temperature, if no larger quantity of water is withdrawn at 14, until such time as the temperature in this space reaches the desired temperature. Thereafter, if the compressor 20 continues to operate, the power consumption of the refrigerating system is automatically reduced because liquid refrigerant rises from the coil 30 and overflows into the heat interchanger 34 where the excess heat absorbing power of the refrigerant is utilized by the evaporation of the liquid refrigerant to cool the condenser 22 at the condensing area or zone and thus reduce the head pressure in the condenser and reduce the load on the motor-compressor unit 20. The amount of liquid refrigerant placed in the system is such that there cannot be any liquid refrigerant overflow beyond the interchanger 34 into the pre-cooler 35. The pre-cooler 35 is in the path of air rising through the space 23 and thus the evaporated refrigerant returning to the compressor 20 is cooled substantially to atmospheric temperature before admission to the compressor if the refrigerant should have become heated above atmospheric temperature in the interchanger 34.

It is within the purview of this invention that the motor-compressor unit 20 shall operate continuously without stopping for temperature adjustments, and in such cases, when the water has been cooled in the tank 10 and only enough refrigeration is required to maintain the water in a cooled condition, that the overflow liquid refrigerant into the interchanger 34 shall operate to reduce the head pressure in the condenser and hence also the power consumption because of the reduced refrigerant pressure differential through which the compressor must compress the refrigerant. This advantage is obtained because the interchanger 34 cools the condenser to such an extent that the pressure differential between the suction and head pressures in the refrigeration system is reduced to a minimum.

While I have described my overflow interchanger principle as applied to a water cooler in connection with a continuously operating refrigeration system, it is to be understood that this invention may be applied to objects to be cooled other than water.

Under certain conditions, it may be desirable to avoid a continuous operation of the motor-compressor unit 20, particularly where there is likely to be a long period of no demand for cooled water. Under such circumstances, a control may be provided to stop the motor-compressor unit after a sufficient amount of water has been cooled in the tank 10 to provide the necessary reserve capacity. To this end, a thermostatic bulb 60 may be placed in the upper part of the tank 10, and this bulb may operate a snap switch 61 through the medium of an expansible bellows 62 and thus cause the motor to start and stop in accordance with the water temperature in the

upper part of the tank 10. In this type of apparatus the refrigeration capacity of the system while it operates may be greater than can be consumed by the thermal exchange between the evaporator and the liquid to be cooled. Under such circumstances the system tends to continue to operate with a greater power consumption than is necessary, notwithstanding the automatic control above referred to, and hence it is within the purview of this invention to utilize the advantages of my condensing area heat interchanger with an intermittently operating refrigerating system as well as with a continuously operating one.

Where the refrigerating system is designed to operate continuously, that is, without an automatic control for stopping and starting the compressor in accordance with temperatures prevailing in the apparatus, a manual control may be provided to control the starting circuits of the motor and to turn off the current when desired. To this end, the manually operable snap switch 51 closes the electric circuit 53 and starts the motor. This is accomplished by the starting relay 54 which operates to energize the common lead 55, the starting lead 56 and the running lead 57 which carry the current to the motor-compressor unit 20. After the motor-compressor unit 20 has passed its starting period and has attained sufficient speed, the starting relay 54 opens the connection to and deenergizes the starting lead 56 and the motor-compressor unit continues to operate by the flow of current through the leads 55 and 57 in the well-known manner. Starting relays of the character designated at 54 are in common use and it is deemed unnecessary further to describe them. After the motor has started, the refrigerating system continues to operate and cool the liquid in tank 10 in the manner heretofore described.

While the form of embodiment of the invention as herein disclosed, constitutes a preferred form, it is to be understood that other forms might be adopted, all coming within the scope of the claims which follow.

What is claimed is as follows:

1. Refrigerating apparatus comprising a vertically disposed tank for liquid to be cooled, means for introducing liquid into the upper part of said tank, means for withdrawing liquid from the lower part of said tank, an evaporator in thermal exchange with said liquid, a refrigerant translating device and a condenser connected to said evaporator, and means for cooling said condenser at the condensing area by refrigerant overflow from said evaporator.

2. Refrigerating apparatus comprising a tank for liquid to be cooled, means for introducing liquid into the upper part of said tank, means for withdrawing liquid from the lower part of said tank, an evaporator in thermal exchange with said liquid, an automatic expansion valve preventing a fall in refrigerant pressure in said evaporator below a predetermined minimum, said valve introducing refrigerant into the lower portion of said evaporator, a refrigerant translating device and a condenser connected to said evaporator, and means for cooling said condenser at the condensing area by refrigerant overflow from the upper portion of said evaporator.

3. Refrigerating apparatus comprising a vertical tank for liquid to be cooled, means for introducing liquid into the upper part of said tank, means for withdrawing liquid from the lower part of said tank, a vertically disposed evaporator in

- thermal exchange with said liquid, an automatic expansion valve responsive to refrigerant pressure within and discharging refrigerant into the lower portion of said evaporator, a condenser discharging refrigerant into said expansion valve, a refrigerant translating device discharging refrigerant into said condenser and receiving refrigerant from the upper portion of said evaporator, and an automatic control governing the 5 operation of said translating device in accordance with the temperature of the liquid in the upper part of said tank.
4. Refrigerating apparatus comprising a vertical tank for liquid to be cooled, means for introducing liquid into the upper part of said tank, means for withdrawing liquid from the lower part 10 of said tank, an upwardly directed sinuously arranged pipe forming an evaporator in thermal contact with said liquid, an automatic expansion valve responsive to refrigerant pressure within and discharging refrigerant into the lower portion of said evaporator, a condenser discharging refrigerant into said expansion valve, a refrigerant translating device discharging refrigerant into said condenser and receiving refrigerant from the upper portion of said evaporator, and 15 an automatic control governing the operation of said translating device in accordance with the temperature of the liquid in the upper part of said tank.
